HEIGHT GAUGE

Percy Aiken, Minneapolis, Minn., assignor to
General Mills, Inc., a corporation of Delaware

Application September 22, 1945, Serial No. 617,945

5 Claims. (Cl. 33—163)

1

This invention relates to height gauges of the type shown in the patent to Nystrom No. 2,354,137 dated July 18, 1944.

An object of this invention is the provision of a simpler, and more efficient form of such gauge and one which can be economically produced.

Another object is the provision of a gauge of this type in which the platform is automatically held parallel to the base for all settings of the same.

These and other objects of the invention as will hereinafter appear are accomplished by this invention which is fully described in the following specification and shown in the accompanying drawings in which

Figure 1 is a perspective view of the height gauge showing the platform raised;

Fig. 2 is a vertical section on the line 2 of Fig. 1; and

Fig. 3 is a partial elevated vertical section showing a modified form of the adjusting nut.

The embodiment shown in Figs. 1 and 2 comprises base 10 having a vertical opening 12 at one end in which is pressed a cylindrical standard 14 drilled and tapped at its upper end to receive a shoulder cap screw 16 which has its shoulder bearing on the upper end of the standard, said shoulder being threaded to receive a locking nut 18, the purpose of which will later be explained.

A platform 20 has an integral sleeve 22 formed thereon, this sleeve being lapped on the inside for an accurate fit on the standard 14 which itself is accurately ground so that a snug sliding fit is obtained.

The upper end of the sleeve is threaded at 24 to receive a relatively long hollow nut 26 which bears on the upper end of the standard. The locking nut 18 has a slight up and down motion between the top of the screw 16 and the top of the adjusting nut 26 and serves, when screwed down, to secure the nut 26 in any adjusted position.

The outer end of the platform 20 has seated therein a guide pin 30 which extends down into a hole 32 which it fits quite closely so that there is relatively little rotative movement between the platform and the base. The pin 32 is shorter than the depth of the hole so that the platform may be completely lowered to rest on the base. A helical tension spring 34 extends through hole 36 in the base where it is held by a pin 38, the latter lying in a shallow trough in the bottom of the base which retains the pin in place but renders it readily removable for disassembling the

2

spring from the base. The upper end of the spring extends into a hole 40 on the under side of the platform and the spring is retained by means of a pin 42. The arrangement of connecting the spring in the holes also permits the platform to be lowered completely to where it rests on the base 10.

The lower surface of the base is preferably relieved by a longitudinal slot 44 leaving two bottom faces 46 which are accurately ground to flatness for use on a surface plate. The upper surface 50 of the platform is ground and lapped into accurate parallelism with the faces 46.

It will be noted that the spring 34 aids gravity in drawing the platform 20 and the adjusting nut 26 always into a position where any backlash due to the screws will be removed. The placing of the spring on that side of the standard on which lies the platform itself serves also to aid gravity in maintaining the platform in the same relative position with respect to the standard. Blocks 60 are then used on the platform, the upper and lower surfaces of these blocks being ground and polished into accurate parallelism.

In use, the platform, with a given block thereon, is raised until the finger 70 of the dial indicator resting on the surface plate S shows that the top surface of the block is a predetermined height above the surface S of the surface plate on which the height gauge is placed.

When the top surface 62 of the block 60 has been set to a desired height, or if desired, the top surface 50 of the platform 20, it set to a desired height above the surface S of the surface plate, the lock nut 18 is screwed down against the adjusting nut 16 thereby locking the gauge in the adjusted position. Either the top surface 50 of the platform, or the top surface 62 of the block may then be used as a reference plane from which to measure heights of other elements of a piece being checked by means of the finger 70 of the dial indicator which all the while rests on the top of the surface plate S.

Some people prefer not to use a lock nut, and Fig. 3 shows a form in which the standard 114 is provided with a shoulder cap screw 116, the shoulder bearing on the top of the standard. About this shoulder rotates an adjusting nut 126 which is threaded on the upper end of a sleeve 124.

While I have shown and described but a few forms of my invention it will be understood that it is capable of many modifications. Changes, therefore, in the construction and arrangement may be made which do not depart

from the spirit and scope of my invention as disclosed in the appended claims.

I claim as my invention:

1. A height gauge having a base, a standard of uniform diameter rising from the base, a platform having a sleeve slidably mounted on the standard, means for preventing rotation of the platform with respect to the standard, a nut rotatably mounted on said standard and being threaded to the top of said sleeve and having a portion overlapping the top of the standard, the sleeve being of minimum thickness between the nut and the standard, the bottom surface of the base and the top surface of the platform being parallel for all adjusted positions of the platform, a tension spring connected between the base and platform assisting the action of gravity on the platform for preventing backlash between the nut and sleeve and for holding the nut firmly down against the upper end of the standard, and a screw threaded into a hole in the top of the standard, said screw having a shoulder about which the nut rotates, the shoulder being longer than the thickness of the overlapping portion of the nut so as to permit the nut to rotate freely and which threads down to press the overlapped portion of the nut against the top of the standard.

2. A height gauge having a base, a standard of uniform diameter rising from the base, a platform having a sleeve slidably mounted on the standard, means for preventing rotation of the platform with respect to the standard, a nut rotatably mounted on said standard and having a screw threaded connection with said sleeve, the bottom surface of the base and the top surface of the platform being parallel for all adjusted positions of the platform, a tension spring connected between the base and platform assisting the action of gravity on the platform for preventing backlash between the nut and sleeve and for holding the nut firmly down against the upper end of the standard, a screw threaded into a hole in the top of the standard, said screw having a shoulder about which the nut rotates, and having a larger screw-threaded portion above the shoulder, and a head above said portion, and a lock nut threaded on said portion, the lock nut when backed off against the head being out of engagement with the nut so as to permit the nut to rotate and locking the nut when in engagement therewith, the thickness of the locking nut being less than the height of the threaded portion above the shoulder.

3. A height gauge having a base, a standard rising from the edge of the base, a platform having a sleeve at the edge thereof slidably mounted on the standard, a pin mounted beneath the platform and slidably in a hole in the base preventing rotation of the platform with respect to the standard, a nut rotatably mounted on the standard and having a screw threaded connection with the sleeve, the bottom surface of the base and the top surface of the platform being parallel for all adjusted positions of the platform, a threaded member rising from the standard above the nut, a locking disk carried by the threaded member to abuttingly engage the nut for locking it in a pre-set position, said disk and nut being of substantially the same diameter and each having a

roughened portion and adjoining the other for manually maintaining the nut adjustment while rotating the locking disk, a first recess in the lower face of the platform, a second recess in the upper face of the base opposite said first recess and extending to the lower face of the base, a shallow trough in the lower face of the base located at the recess opening, a spring anchored in the first recess and extending through the second recess, and a pin positioned in said trough and extending through the spring to hold the spring in the recess.

15 4. A height gauge having a base, a standard rising from the base, a platform having a sleeve slidably mounted on the standard, a pin mounted beneath the platform and slidably in a hole in the base preventing rotation of the platform with respect to the standard, the pin extending below the platform a distance less than the depth of said hole to permit the platform to become lowered completely to rest on the base, an adjustment nut rotatably mounted on the standard and threaded to the sleeve, the bottom surface of the base and the top surface of the platform being parallel for all adjusted positions of the platform, a threaded member rising from the standard, a cylindrical locking disk carried by the threaded member to be screwed down on the nut to lock same in its present position, said nut and disk having substantially the same diameter and having adjoining roughened portions for manually maintaining the nut adjustment while locking by means of the disk.

20 5. A height gauge having a base, a standard of uniform diameter rising from the base, a platform having a sleeve telescoped on the standard said sleeve being of over-all uniform minimum thickness, means to prevent rotation of the platform with respect to the standard, a sleeve nut rotatably mounted on the standard and having a portion overlapping the top of the standard, said nut screwed over the sleeve, a threaded member rising from the standard, a locking disk carried by the threaded member to screw down upon the sleeve nut pressing the overlapping portion against the standard to lock the sleeve, a first recess in the lower face of the platform, a second recess in the upper face of the base opposite said first recess, and a tension spring connected between the base and platform for preventing backlash between the nut and sleeve, the ends of the spring being connected to the base and platform in said recesses to permit the lower face of the platform to be lowered against the upper face of the base.
